(57) **CLAIM**

The ornamental design for a hat, as shown and described.

DESCRIPTION

FIG. 1 is a front view of a hat showing my new design;

FIG. 2 is a left side view thereof;

FIG. 3 is a right side view thereof;

FIG. 4 is a perspective view thereof;

FIG. 5 is another perspective view thereof;

FIG. 6 is a rear view thereof;

FIG. 7 is a top view thereof; and,

FIG. 8 is a bottom view thereof.

The dashed broken lines in FIGS. 1-7 illustrate stitching which forms no part of the claimed design.

The broken lines in FIG. 8 illustrate boundaries which form no part of the claimed design and the relatively light portions within the broken lines illustrate portions of the hat which form no part of the claimed design.

1 Claim, 8 Drawing Sheets
